Primary Examiner—Caron Veynar*Assistant Examiner*—Abraham Bahta(74) *Attorney, Agent, or Firm*—Nixon Peabody LLP(57) **CLAIM**

We claim the ornamental design for a “rotating drumstick display,” as shown and described.

DESCRIPTION

FIG. 1 is a perspective view of a rotating drumstick display holding drumsticks showing our new design.

FIG. 2 is a perspective view of the rotating drumstick display shown in FIG. 1 with interior dividing walls shown.

FIG. 3 is a perspective view of the rotating drumstick display shown in FIG. 1 with interior dividing walls shown holding drumsticks.

FIG. 4 is a front-side view of the rotating drumstick display shown in FIG. 1 with interior dividing walls.

FIG. 5 is a back-side view of the rotating drumstick display shown in FIG. 1 with interior dividing walls.

FIG. 6 is a left-side view of the rotating drumstick display shown in FIG. 1 with interior dividing walls.

FIG. 7 is a right-side view of the rotating drumstick display shown in FIG. 1 with interior dividing walls.

FIG. 8 is a top view of the rotating drumstick display shown in FIG. 1; and,

FIG. 9 is a bottom view of the rotating drumstick display shown in FIG. 1.

The broken line showing of drum sticks in FIGS. 1 and 3 is included for the purpose of illustrating environmental structure and forms no part of the claimed design.
